CLAIM

The ornamental design for an insulated wire with partially exposed conductor, as shown and described.

DESCRIPTION

FIG. 1 is a top view of the “insulated wire with partially exposed conductor”.

FIG. 2 is a front view of the “insulated wire with partially exposed conductor”.

FIG. 3 is a bottom view of the “insulated wire with partially exposed conductor”.

FIG. 4 is a right cross-sectional view and a left cross-sectional view of the “insulated wire with partially exposed conductor” along cross-sectional lines A-A; and,

FIG. 5 is a right cross-sectional view and a left cross-sectional view of the “insulated wire with partially exposed conductor” along cross-sectional lines B-B.
